CASE FOR A HAIR CURLER KIT OR SIMILAR ARTICLE

Robert S. Waters, Oak Brook, Ill., assignor to Sunbeam
Corporation, Chicago, Ill.

Filed Jan. 27, 1969, Ser. No. 15,520

Term of patent 14 years

Int. Cl. D28—03

U.S. Cl. D86—10

Fig. 1.

Fig. 2.

Fig. 3.

Fig. 4

FIG. 1 is a perspective view of a case for a hair curler kit or similar article embodying my invention;

FIG. 2 is a top plan view thereof;

FIG. 3 is a side elevational view, the opposite side being substantially a mirror image thereof; and

FIG. 4 is a rear elevational view thereof.

I claim:

The ornamental design for a case for a hair curler kit or similar article, as shown and described.
